UNITED STATES PATENT OFFICE.

WILLIAM F. BALDWIN, OF GRAYVILLE, ILLINOIS.

FIRE-ENGINE.

SPECIFICATION forming part of Letters Patent No. 292,276, dated January 22, 1884.

Application filed August 28, 1883. (No model.)

To all whom it may concern:

Be it known that I, WILLIAM F. BALDWIN, a citizen of the United States, residing at Grayville, in the county of White and State of Illinois, have invented a new and useful Improvement 5 in Fire-Engines, of which the following is a specification.

My invention relates to that class of fire-engines which consists of pumps usually operated by hand to draw water from cisterns to be delivered upon a fire or elsewhere; and it has for its object to provide means whereby any number of cisterns may be adapted to receive the same pump and its operating-gear, 10 and the gear adapted to operate one or more pumps by hand or animal power, and to be readily removed from its fastenings.

To this end my invention consists in the construction and combination of parts hereinafter described and claimed, reference being had to the accompanying drawings, in which—

Figure 1 is a vertical section of part of a cistern, showing my invention. Fig. 2 is a plan view of the same. Fig. 3 is a perspective drawing of the thimble, which is secured in the top of a cistern. Figs. 4 and 5 are detail views in elevation and plan, and Fig. 6 is a detail in perspective.

A represents a cistern buried in the earth. 30 B is a thimble which I fix in the top of the cistern, to furnish bearings for the pump and my driving-gear.

C represents a pump of any suitable construction, operated by two pistons, D, reciprocated alternately by two eccentrics, E, on two separate shafts, F, in the same line. The pump C is supported by a frame, G, which hangs in recesses a in the thimble B.

H is a support for the inner ends of shafts 40 F and for the master-wheel I. The shafts F rotate in the two ends of one common bearing in support H. The master-wheel I rotates upon a stud, J, projecting up from the center of support H. Each end of this support is bifurcated, resting in recesses b in the thimble B, to give it a firm bearing. The master-wheel is provided with beveled-gear teeth on its under side, engaging a pinion, K, on shafts F. The upper face of the master-wheel is provided 45 with dovetailed grooves to receive levers L, provided with metallic shields M, dovetailed to fit into slots N removably, whereby the

master-wheel may be revolved when desired, and the levers removed and stored away, leaving the pump and motor connected, the top of 55 the device being flush with the ground. The levers may be provided with means to hitch horses to them, if desired. Revolving the master-wheel causes the pinions K, their shafts F, and the eccentrics E to revolve at a greater 60 speed, thus working the pump. The delivery-pipe Q of the pump rises through the thimble B at P, where it may be provided with the usual means for coupling with a hose, the levers L being arranged to pass freely over 65 the hose. The web of the master-wheel is hollowed out below, to turn freely over the eccentrics.

R is a circular ledge in the thimble, in which the rim of the master-wheel may bear to prevent 70 its rocking when fitted freely on its central bearing. This master-wheel is practically the cover to the cistern. It may be raised from its bearing, the support H may be raised from its seat in the thimble, and the pump-frame 75 may be raised from its seat, thus removing the working parts from the cistern, so that they may be all used in another cistern provided with a similar thimble.

Some of the advantages of this fire-engine 80 over common hand fire-engines are as follows: This engine is in position for use all the time, only requiring the levers and hose to be attached, while portable engines cannot be started for a fire in country villages until a 85 sufficient force to haul them arrives. Then the portable engine must come to this same cistern for its water and stand there to be worked. The cost of one portable engine would provide a number of my engines, each located 90 ready for use in the most populous portions of a town, where cisterns are usually located. The circular motion, whereby either hand or horse power may be used, is a great advantage, for with my engine two men and a horse 95 can do good work, and the addition of more men and more horses will increase the results until the power is sufficient to revolve the levers at the greatest speed that the men and horses can travel. When the levers are removed, the works are level with the top of the ground and out of the way, and protected from dirt.

I provide two shafts, F, because it is imprac-

ticable to fit two pinions, K, to engage the teeth of one master-wheel at the same instant, and when both pinions are on one shaft they cause it to twist, producing friction. I place the two shafts in line in order that pinions K may bear at opposite points with balancing effect on wheel I.

What I claim as my invention, and wish to secure by Letters Patent, is—

- 10 1. A thimble secured in the top of a cistern and a pump removably hung in said thimble, in combination with a horizontal cover journaled to rotate over the mouth of said thimble, having means for attaching handles to its upper side and means for communicating motion to said pump, as shown and described.
- 15 2. A thimble having two sets of recesses secured in the top of the cistern, a pump adapted to hang in one set of said recesses, and a cross-bar adapted to rest in the other set of said recesses, in combination with a cover journaled to rotate upon said cross-bar, having sockets on its upper face to receive handles, and gear-teeth on its lower face to communicate with said pump, as shown and described.
- 20 3. The thimble B, having recesses *a*, secured in the top of a cistern, in combination with a pump having a frame, G, provided with lugs adapted to rest in said recesses, as shown and described.
- 25 4. The combination, with a thimble permanently fixed in the top of a cistern, said thimble having shouldered recesses in it, of a pump

having a frame provided with shoulders or 35 tenons to rest in said recesses, substantially as described, whereby said pump may be suspended in the cistern, or the same pump may be removed intact from the cistern and from the thimble without loosening any binding 40 devices.

5. The combination, with a thimble adapted to rest in the top of a cistern, having recesses *b* in it and a pump suspended by it, of a support, H, adapted to rest in said recesses, said 45 support having the stud J and a bearing for shafts F, as described.

6. The thimble B, having recesses *a* and *b*, the frame G, supported thereby, a pump supported in said frame, the eccentrics E, operating said pump, the pinions K, the master-wheel I, engaging them, the support H, provided with the stud J and bearings for a shaft, in combination with the two shafts F, journaled in said bearings and in frame G, each of 50 55 said shafts carrying one of the eccentrics E and one pinion-wheel, K, as shown and described.

7. The thimble B, having recesses *b* and the bearing R, and the support H, adapted to rest 60 in said recesses, having a stud, J, in combination with the master-wheel I, journaled on said stud, and provided with a peripheral edge adapted to rotate in bearing R, as described.

WILLIAM F. BALDWIN.
